UNITED STATES PATENT OFFICE.

THOMAS H. DEVANEY, OF LONG BRANCH, NEW JERSEY.

DESIGN FOR A BOILER-TUBE PLUG.

56,554.

Specification for Design.

Patented Nov. 9, 1920.

Application filed March 23, 1920. Serial No. 368,146. Term of patent 14 years.

To all whom it may concern:

Be it known that I, THOMAS H. DEVANEY, a citizen of the United States, and resident of Long Branch, in the county of Monmouth and State of New Jersey, have invented a certain new, original, and ornamental Design for Boiler-Tube Plugs, of which the following is a specification, reference being had to the accompanying drawing, forming part thereof.

The figure is an elevation of a boiler-tube plug, showing my new design.

I claim:

The ornamental design for a boiler-tube plug, as shown.

Signed at New York city in the county of New York and State of New York this 17th day of February A. D. 1920.

THOMAS H. DEVANEY.
